United States Patent Office

Des. 187,863
Patented May 10, 1960

187,863

REAR VIEW MIRROR

Frederic P. Plotkin, Los Angeles, Calif.

Application September 4, 1959, Serial No. 57,433

Term of patent 14 years

(Cl. D14—6)

Fig. 1.

Fig. 2.

Fig. 3.

Fig. 4.

Fig. 1 is a front elevational view of a rear view mirror, showing my new design;

Fig. 2 is a side elevational view thereof;

Fig. 3 is a rear elevational view thereof; and

Fig. 4 is a top plan view thereof, with the support shown broken away for purposes of illustration.

The dominant features of my design reside in the portions shown in full lines.

I claim:

The ornamental design for a rear view mirror, substantially as shown and described.
